UNITED STATES PATENT OFFICE.

JACOB W. ELVYN, OF CHICAGO, ILLINOIS.

ADVERTISING DEVICE.

1,194,727.

Specification of Letters Patent. Patented Aug. 15, 1916.

Application filed March 13, 1916. Serial No. 83,762.

To all whom it may concern:

Be it known that I, JACOB W. ELVYN, a citizen of the United States, residing at Chicago, in the county of Cook and State of Illinois, have invented a certain new and useful Improvement in Advertising Devices, of which the following is a full, clear, concise, and exact description, reference being had to the accompanying drawings, forming 10 a part of this specification.

My invention relates to amusement devices, particularly to puzzles, and is concerned especially with a puzzle device which may be used practically and attractively for 15 advertising purposes, being peculiarly constructed for transmission through the mails.

In accordance with my invention I provide a card, of such size that it may conveniently be sent through the mails, either 20 by itself or in an envelop, and I score or perforate upon predetermined lines on said card to outline geometrical figures preferably of uniform size and shape. The unitary construction which thus results accomplishes 25 the first purpose set forth and suitable printing matter may be impressed upon the face of the card, on one or both sides. The recipients then divide the card according to the perforated lines, or scoring, thus producing 30 the intended multiplicity of similar portions which may, for the purposes of amusement, be shuffled and then laid together in such a way as to join properly the printed matter thereon. If desired, the various 35 units may be variously colored, or sets of units may be variously colored, so that when laid together they may produce an effective geometrical design, thus adding to the interest in laying the units together. As

40 a further feature of my invention, I so dispose the printing matter thereon that the lines of some of the letters appear coincident with the perforated lines or scoring, and in this way the proper joining of the units is made a little more difficult. In so 45 disposing the printed matter upon the card, the certain lines of the letters readily appear when the units are laid together, but practically disappear to the eye when the units 50 are separated.

My invention is illustrated in the accompanying drawing in which the card itself is illustrated at *a*, the entire card being divided up into diamond shaped units of uniform size by means of perforated lines or scoring *b b*, thus, although the card is originally integral, the component units may be readily detached from each other to form the puzzle set. As shown, the printed matter is so disposed on the card that certain 60 of the letters thereof are coincident with the perforated lines or scoring, for the purpose hereinbefore pointed out. The fact that the puzzle set is originally in integral condition, not only makes it easily transmissible through the mails, but also simplifies the printing, as will be apparent. It also simplifies handling of the puzzle set since each card constitutes a set and thus eliminates the inconvenience of printing the 70 units separately and apportioning the sets by distribution as might otherwise be necessary.

The complete aggregated units determine the periphery of the card and also presents 75 within the periphery a geometric design.

It will be obvious to those skilled in the art that other shapes of units may be employed without departing from the spirit and scope of my invention, and it is my intention therefore not to be limited to the diamond shaped units which I have illustrated. I prefer, however, to use a geometrical design which contains vertical lines since such a design lends itself more effectively 80 to the further idea of making certain lines of the printed matter coincide with certain of the perforated lines or scorings.

It will be noted that the figure I have shown is a geometrically regular one, which 90 is the preferred form since such a figure may be made to assume its regularity even though the sections are misplaced so far as printed matter is concerned. In this way, the matter of laying the sections together is made 95 a bit more difficult.

I claim as new and desire to secure by Letters Patent:

1. A card divided up into sections by perforated lines or scorings, printed matter on 100

said card as a whole, certain lines of said printed matter coinciding with certain of said perforated lines or scorings.

2. A card divided up into diamond-shaped sections by perforated lines or scorings, printed matter on said card as a whole, certain lines of said printed matter coincid-

ing with certain of said perforated lines or scorings.

In witness whereof, I hereunto subscribe ¹⁰ my name this 11th day of March, A. D. 1916.

JACOB W. ELVYN.
